DUST AND SMOKE DENSITY MEASURING
DEVICE

Alfred Walter Simon, Birmingham, Leonard Carothers Kron, Ensley, and Henry Raymond, Pratt City, Ala.

Application August 14, 1931. Serial No. 557,192

5 Claims. (Cl. 88—14)

This invention relates to dust or smoke concentration meter devices such as is disclosed in copending application Serial No. 390,634, filed September 5, 1929.

6 In the above identified copending application a dust or smoke concentration meter device is disclosed in which a beam of radiation is passed through a predetermined known and constant distance, the smoke or dust containing gas or a 10 representative sample thereof is passed through the beam and the emergent radiation utilized by means of a light sensitive device to energize recording or indicating mechanism, graduated to indicate the density of the gas.

15 In the apparatus disclosed the beam of light is projected through a light permeable window for a predetermined distance, thence through a glass window to the radiation sensitive device. The smoke or dust laden gases are circulated between the two windows. To prevent the dust 20 and smoke from collecting upon and interfering with the transmission of the radiation through the windows mechanical wiping means are provided to keep the windows clean.

25 It is found however that when the smoke or dust containing gases are "wet" or moist with water, or volatile substances such as oil, tar, paraffines and the like, the windows tend to become clouded or smeared with the condensates 30 of such substances and that the mechanical wiping means are not entirely effective in keeping the windows clean.

It is one of the objects of this invention to improve the mechanical cleaning of the light 35 transparent windows of the above identified application.

It is another object of this invention to provide means to eliminate deleterious condensate materials from the light transparent windows of 40 the above identified application.

It is another object of this invention to improve the operating characteristics of the dust concentration meter of the above identified application.

45 Other objects and advantages will become apparent as the invention is more fully disclosed.

In accordance with the objects of the present invention we propose to supplement the wipers by a stream of water or other liquid solvent to the condensing materials which is directed upon the windows; or to keep the windows hot by any convenient means so that moisture or other condensate materials will not be apt to condense upon or to remain therein if it does condense.

55 Before further disclosing the nature and scope

of the present invention reference should be made to the accompanying drawings wherein:

Fig. 1 is a sectional side elevation view of one end of the dust concentration meter device illustrating one modification of the improved window cleaning feature of the present invention; 60

Fig. 2 shows a cross-sectional view of the same illustrating a second modification;

Fig. 3 illustrates a third modification;

Fig. 4 is a cross-sectional view of the same; 65 and

Fig. 5 is a longitudinal section disclosing the entire meter device of the present invention with the electrical circuits shown schematically.

Referring to Fig. 1, the details of the invention 70 for carrying out the heating of the window with a hot air stream are shown. In this figure, 1 represents one end of the dust meter device of the above identified application, in particular, the end carrying the Mazda lamp or light source;

2 is the radiation permeable window, the surface of which opposite to the light source 5 is to be kept free of moisture. A second window 3 is interposed between the first window 2 and the lamp 5 and lens 6 (the lens 6 itself might perform this function if of heat resisting glass).

Thru the cylindrical chamber 4 between the two windows 2, 3, heated air is circulated. This heated air comes from an air line 7, passes thru a heater 8, and then enters the space 4 thru the pipe 9 and leaves thru the pipe 10. In place of heated air, dry steam or other light permeable

gas can be used. The air if not perfectly clean 80 can be filtered in any convenient manner before admission to the chamber 4.

90 A second modification of the present invention is illustrated in Fig. 2 wherein two small water jets are played upon the window surface, the jets so shaped as to spread the water well over the windows and symmetrically placed with respect to the wiper blade and the light beam so as not to interfere with either. The water absorbs some of the light and heat energy from the lamp 5, but this, as long as it is a constant fraction, is immaterial, since it is corrected for in setting 95 the meter device to a clear reading. In order to keep this fractional part constant, the water flow must be kept substantially constant.

100 In Fig. 2, 20 indicates the casing of the meter device in section; 21, the surface of the window facing the gas stream; 22, the blade of the wiper for the window; 23, the spring and holder for the wiper blade 24, the shaft actuating the wiper; and 25, the water sprays for the windows.

105 Means such as outlet 26 can be provided to carry 110

110

115

120

off the water from the interior of the recorder pipe 20.

The second alternative (Fig. 3) is particularly practical, where the moisture is not excessive and comprises means to keep the surface of the window hot to prevent the condensation of moisture thereon, and to evaporate any condensate droplets which might accidentally be deposited on the windows.

10 Referring to Fig. 3, one means of keeping the window warm comprises suitable electric heating elements placed adjacent the windows. The glass must be a heat resisting glass such as pyrex, or quartz. A second means may comprise, for example, a stream of heated air impinging on the window to keep it hot. These two means may be combined to form the complete modification shown in Fig. 3. Since hot air might effect the thermopile, or the light, if it came in contact with it, the double window should be used, the second window being interposed between the lamp or thermopile and the hot air chamber. This makes it possible to keep the first window hot and still have the light or thermopile chamber cold. If desired, these light or thermopile elements can be placed some distance from the window so that the hot air will not affect them. The hot air can be supplied by heating electrically and forcing it thru by means of a small fan, or better, air from a compressed air line can be used after being passed thru a suitable heating arrangement, such as is indicated in Fig. 1 at 8.

15 In place of heated air impinging on the windows the latter can also be heated by means of the heating coil placed along its periphery, the center of the window being heated by heat conducted from the periphery of the window to the center by the air stream. This is specifically shown in Fig. 3, where 31 represents the window and 35 the heating coil. The latter is embedded in a refractory and pressed close to the surface of the window adjacent the casing 30. The heated or unheated air is conducted in 20 by one of the pipes 32 and leaves by the other. Fig. 4 is a cross-sectional view of the same.

25 Referring to Fig. 5 the meter device of the present invention is shown mounted to record the density of gases flowing in a conduit, pipe, smokestack or the like 40. The gas chamber 41 of the meter is substantially a by-pass conduit for pipe 40, the gases flowing in pipe 40 being conducted thereto by means of conduit 42 and therefrom by conduit 43 substantially as indicated by arrows.

30 As shown, at each end of chamber 41 are the radiation permeable windows 2-2' spaced a determined distance apart. These windows it is desired to maintain substantially free from deleterious and radiation obscuring deposits and condensate materials from the gases flowing through the chamber. Mechanical wiping means 22-22' have been utilized but it has been found that with certain types of gases these are not entirely effective due to the fact that most gases contain radiation absorbing volatile fluids such as water, tar and the like which tend to condense thereon. Accordingly means must be provided as illustrated in Figs. 1 to 4 inclusive to prevent the condensation of these materials upon the window faces.

35 In Fig. 5 the specific means disclosed is the means substantially set forth in Fig. 1 and the same numerals applied in Fig. 1 are applied in 40 Fig. 5. The means disclosed in Figs. 2 to 4 in-

clusive however may be substituted therefor without departing essentially from the nature and scope of the present invention.

45 In operation the radiation evolved from light source 5 energized by electric current from source 44 passes through lens 6 and thence through light permeable windows 3 and 2 spaced apart to form a heating chamber suitable for the purposes of the present invention. The radiation then passes through chamber 41 through light permeable windows 2'-3' spaced similarly as are windows 3-2, then through lens 6' where it is concentrated upon radiation sensitive device 45. The current flow in device 45 in response to variations in the radiation falling thereon energizes measuring and/or recording instrument 46. In the heat chambers between the light permeable windows 3-2 and 2'-3', heated air is passed substantially as is shown and heretofore described with respect to Fig. 1. Mechanical wiping means 22-22' operates to continuously maintain the face of windows 2-2' adjacent the gas stream substantially free from radiation absorbing deposits from the flowing gas stream while the heated air prevents the condensation of light obscuring condensates thereon from the gas stream. In this manner, the true density of the gas flowing between windows 2-2' can be at all time accurately determined.

50 It is apparent from the above specification and drawings that there may be many modifications and departures made of the present invention without departing essentially from the nature and scope thereof as may be set forth in 110 the accompanying claims.

55 What is claimed:

1. A dust concentration meter device comprising a chamber, means to pass smoke laden gases into and out of said chamber, two radiation transparent windows disposed in opposite walls of said chamber between which the smoke laden gases are conducted, wiper means to maintain the inside faces of said windows substantially free from radiation absorbing deposits, 115 means to mechanically operate said wiper means, means to project a fluid upon the said inside faces of said windows, means to drain said fluid from said chamber, means disposed adjacent one of said windows and exteriorly said chamber 120 to project radiation through said window into said chamber and through the opposite window, radiation sensitive means disposed adjacent the said opposite window and exteriorly said chamber to receive the projected radiation, and means 125 to measure the amount of said received radiation.

2. A dust concentration meter device comprising a chamber, means to pass smoke laden gases into and out of said chamber, two radiation 130 transparent windows disposed in opposite walls of said chamber between which the smoke laden gases are conducted, wiper means to maintain the inside faces of said windows substantially free from radiation absorbing deposits, means to 140 mechanically operate said wiper means, means to heat said windows to a temperature sufficient to prevent the deposition on said inside window faces of radiation absorbing condensation products from said gases, means disposed adjacent one of said windows and exteriorly said chamber to project radiation through said window into said chamber and through the opposite window, radiation sensitive means disposed adjacent the said opposite window and exteriorly said chamber 145 to receive the projected radiation, and means to measure the amount of said received radiation.

150

ber to receive the projected radiation and means to measure the amount of said received radiation.

- 5 3. A dust concentration meter device comprising a chamber, means to pass smoke laden gases into and out of said chamber, two radiation transparent windows disposed in opposite walls of said chamber between which the smoke laden gases are conducted, wiper means to maintain the inside faces of said windows substantially free from radiation absorbing deposits, means to mechanically operate said wiper means, means to direct a stream of heated air against the outside faces of said windows to 10 heat said windows to a temperature sufficient to prevent the deposition on said inside window faces of radiation absorbing condensation products from said gases, means disposed adjacent one of said windows and exteriorly said chamber to project radiation through said window into said chamber and through the opposite window, radiation sensitive means disposed adjacent the said opposite window and exteriorly said chamber to receive the projected radiation and means to measure the amount of said received radiation.

- 15 4. A dust concentration meter device comprising a chamber, means to pass smoke laden gases into and out of said chamber, two radiation transparent windows disposed in opposite walls of said chamber between which the smoke laden gases are conducted, wiper means to maintain the inside faces of said windows substantially free from radiation absorbing deposits, means to mechanically operate said wiper means, means to direct a flow of air across the outside faces of said windows and means to heat said air to a temperature sufficient to prevent the deposition on said inside window faces of radiation absorbing condensation products from said gases, means disposed adjacent one of said windows and exteriorly said chamber to project radiation through said window into said chamber and through the opposite window, radiation sensitive means disposed adjacent the said opposite window and exteriorly said chamber to receive the projected radiation and means to measure the amount of said received radiation.

20 5. A dust concentration meter device comprising a chamber, means to pass smoke laden gases into and out of said chamber, two radiation transparent windows disposed in opposite walls of said chamber between which the smoke laden gases are conducted, wiper means to maintain the inside faces of said windows substantially free from radiation absorbing deposits, means to mechanically operate said wiper means, means to direct a stream of heated air against the outside faces of said windows to 25 heat said windows to a temperature sufficient to prevent the deposition on said inside window faces of radiation absorbing condensation products from said gases, means disposed adjacent one of said windows and exteriorly said chamber to project radiation through said window into said chamber and through the opposite window, radiation sensitive means disposed adjacent the said opposite window and exteriorly said chamber to receive the projected radiation and means to measure the amount of said received radiation.

30 6. A dust concentration meter device comprising a chamber, means to pass smoke laden gases into and out of said chamber, two radiation transparent windows disposed in opposite walls of said chamber between which the smoke laden gases are conducted, wiper means to maintain the inside faces of said windows substantially free from radiation absorbing deposits, means to mechanically operate said wiper means, means to direct a flow of air across the outside faces of said windows and means to heat said air to a temperature sufficient to prevent the deposition on said inside window faces of radiation absorbing condensation products from said gases, means disposed adjacent one of said windows and exteriorly said chamber to project radiation through said window into said chamber and through the opposite window, radiation sensitive means disposed adjacent the said opposite window and exteriorly said chamber to receive the projected radiation and means to measure the amount of said received radiation.
